UNITED STATES PATENT OFFICE.

JOHN PLONKA, OF CHICAGO, ILLINOIS.

BOAT-PROPELLING MEANS.

Application filed February 10, 1925. Serial No. 8,122.

To all whom it may concern:

Be it known that I, JOHN PLONKA, citizen of the United States, residing at Chicago, in the county of Cook and State of Illinois, have invented certain new and useful Improvements in Boat-Propelling Means, of which the following is a specification.

This invention relates to boat propelling means, the invention having for an object 10 the provision of a series of propeller wheels of novel construction and having propulsion elements that may be moved into and out of the water as desired.

For further comprehension of the invention, and of the objects and advantages thereof, reference will be had to the following description and accompanying drawing, and to the appended claims in which the various novel features of the invention are 20 more particularly set forth.

Fig. 1 of the drawing is a plan view of a boat showing the same provided with my improved propeller wheels.

Fig. 2 is a face view of one of the wheels. 25 Fig. 3 is an axial sectional view thereof.

In the drawing the reference numeral 10 indicates the hull of a ship that has mounted thereon, at the rear thereof, a transverse shaft 11. This shaft may receive rotation 30 from any suitable means, a drive shaft 12 being shown as operatively connected thereto by means of the bevel gearing indicated at 13. Upon this shaft are fixed three paddle wheels that dip into the water, there being one of these wheels, indicated at 15, 35 at the median line of the boat, and the others being mounted on opposite ends of the shaft and being indicated at 16 in Fig. 1.

Each of these wheels comprises a hub element 20, having screwed or otherwise fixed thereto the inner ends of tubular spokes 21 on which the vanes or paddles 16' of the wheel are slidably mounted to move radially with respect to the wheel. Each vane is 40 fixed at its ends to sleeves 23 that freely encircle the spokes. Each of these sleeves has mounted in a recess therein a pair of spring-pressed pawls 24, 24' that bear on the adjacent spoke, there being a pawl at each end 45 of the sleeve, the respective pawls facing in opposite directions. Each spoke is formed with a pair of radially spaced notches 25, 25' into which the pawls at times selectively project and which serve to retain the paddles 50 in radially adjusted positions.

Slidable within each tubular spoke 21 is a rod 28 that has a pair of cams 29, 29' formed on one side thereof, which cams are adapted at certain times to engage the pawls 24, 24' to lift the same from the notches in 60 the spoke. These rods bear at their inner ends on a pair of circular wedge members 32 that are located within the hub element of the wheel 20 and that are adapted to be moved longitudinally therein, the rods 28 65 being pressed against the wedge members by means of expansion spring such as 33 that bear on the outer ends of the rods. To move the wedge members 32 longitudinally in the hub of the wheel, in order to bring the rise or fall thereof under the rods 21, these wedge members are fixed on a rod 35 that extends through an axial boring 36 in the shaft 11 and has fixed thereto a transverse pin 37 that projects through longitudinal slots 38 70 in the said shaft 11 and is fixed at its end to a collar 39 freely encircling this shaft, this collar being adapted to be engaged by any ordinary lever element 40 fixed on a rock shaft 41 mounted in the hull of the 75 ship.

Normally the paddles 16' lie adjacent the extremities of the spokes, being prevented from sliding downward when at the top of the wheel by the pawls 24' engaging in the notches 25. If it is desired to throw one paddle wheel out of commission, as when the vessel is to be turned around, or for any other reason, the wedge members 32 are shifted to allow the rods 28 to move inward 80 under the pressure of the springs 33, thereby releasing the pawls 24' and allowing the wheel paddles to slide inward when at the top of the wheel, the paddles being retained 85 against falling outward when at the bottom of the wheel by engagement of the pawls 24 in the notches 25'. When the paddles are to be restored to their normal position the wedge members 32 are again shifted to move the rods 28 outward, freeing the pawls 24 90 and thereby allowing the paddles to slide to their outer position when at the bottom 95 of the wheel.

Having thus described my invention, what I claim as new and desire to protect by Letters Patent of the United States is as follows:

1. In a ship, a paddle wheel comprising spokes, sleeves slidably mounted on said spokes, paddles attached to said sleeves, 110

pawl on said sleeves for retaining the same in radially adjusted positions on said spokes, and devices for releasing said pawls.

2. In a ship, a paddle wheel comprising 5 spokes, sleeves slidably mounted on said spokes, paddles attached to said sleeves, pawls on said sleeves for retaining the same in radially adjusted positions on said spokes, and devices for releasing said pawls, said 10 devices comprising rods extending through the said spokes.

3. In a ship, a paddle wheel comprising 15 spokes, sleeves slidably mounted on said spokes, paddles attached to said sleeves, pawls on said sleeves for retaining the same in radially adjusted positions on said spokes, and devices for releasing said pawls, said devices comprising rods extending through the said spokes, and wedge members movable axially in wheel hub for moving said 20 rods in one direction.

4. In a ship, a paddle wheel comprising 25 spokes, sleeves slidably mounted on said spokes, paddles attached to said sleeves, pawls on said sleeves for retaining the same in radially adjusted positions on said spokes,

and devices for releasing said pawls, said devices comprising rods extending through the said spokes, and wedge members movable axially in wheel hub for moving said 30 rods in one direction, and springs engaged with the outer ends of said rods for moving the same in opposite directions to said wedge members.

5. In a ship, a paddle wheel comprising 35 spokes, sleeves slidably mounted on said spokes, paddles attached to said sleeves, pawls on said sleeves for retaining the same in radially adjusted positions on said spokes, and devices for releasing said pawls, said 40 devices comprising rods extending through the said spokes, and wedge members movable axially in wheel hub for moving said rods in one direction, and springs engaged with the outer ends of said rods for moving the same in opposite directions to said wedge 45 members, said rods being formed with cam projections for disengaging the said pawls from the said spokes.

In testimony whereof I have affixed my 50 signature.

JOHN PLONKA.
